CONE WINDER GUIDE

William T. Stearn, Cumberland, Md., assignor to
Celanese Corporation of America, a corpora-
tion of Delaware

Application September 19, 1944, Serial No. 554,748

3 Claims. (Cl. 242—157)

This invention relates to a yarn winding device and more particularly to a novel yarn guide for use on a yarn cone packaging machine.

In devices that draw yarn from a source of supply and, with or without inserting twist therein, wind the yarn into a cone there is usually provided a guide for directing the yarn onto the cone. This guide reciprocates back and forth across the package and also bears against the windings on the package, it being adapted to be carried on a pivoted arm so that when the package reaches a predetermined size the arm actuates a stop mechanism which halts further winding of yarn. The guides employed prior to this invention had a tendency to scuff up the yarn on the package and also to create such friction that extremely hard packages were formed which were difficult to unwind on knitting and like machines.

It is accordingly an object of this invention to construct a guide for cone winding machines that reduces to a minimum the tension exerted on the yarn and the pressure applied to the package during winding by the guide.

Another object of this invention is the provision of a yarn guide in which wear at the contact points is substantially reduced.

A further object of this invention is the provision of a yarn guide in which yarn breakage is substantially eliminated and which enables softer packages to be produced, due to the reduction in guide wear and yarn tension.

Other objects of this invention, together with certain details of construction and combinations of parts, will appear from the following detailed description and claims.

In accordance with my invention I construct, for use in cone winding machines and like winding devices, an anti-friction type of guide comprising a roller guide and roller bail mounted on the pivoted guide arm normally employed on such winding devices.

In the drawing wherein one embodiment of my invention is shown,

Fig. 1 is an end elevational view of my novel yarn guide structure showing it in relation to the cone of yarn being wound, and

Fig. 2 is a top plan view of the same.

Like reference numerals indicate like parts throughout both views of the drawing.

Referring to the drawing the reference numeral 1 indicates the cone of yarn which is being built into a cone on a core 2 of cardboard or other suitable material. This core 2 is adapted to fit on a spindle of a cone winding machine and to be rotated thereby, which spindle and its driving

mechanism are not shown as the present invention is operable with all conventional types of cone winding machines. Operating in timed relation to the rotation of the yarn package is a guide generally indicated by the reference numeral 3. The guide 3 comprises a carriage 4 provided with a tongue 5 forming a V-shape groove therewith, which groove is adapted to receive a polished edge or track 6 of a pivoted guide arm 7. The carriage 4 is caused to reciprocate on the track 6 by means of a rod 8 attached to a projection 9 on the side of the carriage. The rod 8 in the standard machines is operably connected to a cam (not shown) that is driven in timed relation to the rotation of the package 1.

A roller guide 11 having each end rounded, as at 12, in order to prevent damage to the yarn of the package is carried by the carriage 4. Roller guide 11, which is recessed at each end to accommodate a ball bearing 13, is mounted on a stationary spindle 14 supported by a U-shaped holder 15. A forked wire guide 16 is attached to the guide holder 15 or, as shown, to the carriage 4 immediately behind the roller guide 11 for the purpose of preventing the yarn A from leaving a V-groove 17 that is formed in the roller guide 11. The roller guide 11 is preferably formed of polished tool steel and may be of any desired size. For the purpose of building cones from yarn of less than one thousand denier the roller guide should be approximately $\frac{1}{2}$ inch long $\frac{7}{16}$ of an inch in diameter with the V-groove 17 being about $\frac{1}{16}$ of an inch wide and of the same depth. As stated, the roller guide may vary in size, and may also be made of any suitable material. Operating in conjunction with the roller guide 11 is a ball bearing roller-bail 18 journaled in two brackets 19, only one of which is shown, extending from the pivoted guide arm 7.

The yarn A, after leaving the supply package and passing through the tensioning device or devices normally employed on cone packaging machines, is carried over the free running roller-bail 18 through the forked wire guide 16, into the groove 17 of the roller guide 11 and on to the take-up package 1. The roller bail 18 is frictionally rotated by the yarn A while the roller guide 11 is driven by the surface of the rotating package 1, with which it is normally in contact, and at approximately the same linear speed. By employing this invention, there is obtained a reduction in the tension on the yarn and the pressure applied to the package during winding, thus packages which are lower in density are produced. Moreover, fewer ends of yarn are broken and a

more freely unwinding package is produced by the present device than by devices employed prior to this invention.

It is to be understood that the foregoing detailed description is given merely by way of illustration and that many variations may be made therein without departing from the spirit of my invention.

Having described my invention, what I desire to secure by Letters Patent is:

1. A guide for winding yarn onto packages comprising a roller guide having a guide groove therein for receiving and guiding the yarn being wound onto the package being formed, a forked wire guide for maintaining the yarn in the groove and a carriage supporting said roller guide and forked wire guide.

2. A guide for winding yarn onto packages comprising a roller guide having a guide groove therein for receiving and guiding the yarn being wound onto the package being formed, a track, a carriage mounted on said track supporting said roller guide and a roller bail attached to said track.

3. A guide for winding yarn onto packages comprising a roller guide having a guide groove therein for receiving and guiding the yarn being wound onto the package being formed, a forked wire guide for maintaining the yarn in the said groove, a carriage for supporting said roller guide and said forked wire guide and a track upon which said carriage is adapted to slide.

WILLIAM T. STEARN.
